STAMPING MACHINE

Rupert L. Greenleaf, Auburn, Maine

Original application January 30, 1941, Serial No. 376,689. Divided and this application December 2, 1941, Serial No. 421,351

6 Claims. (Cl. 101—305)

This invention relates to an improved stamping machine and is a division of my application, Serial No. 376,689, filed January 30, 1941.

One object of the invention is to provide a stamping machine employing improved locking mechanism for retaining the inking roll in the ink well pad with the right pressure to force the ink into the inking roll when the machine is in use and in lowered or retracted position.

Another object of the invention is to provide a stamping machine wherein the locking mechanism is automatically operated by shifting of the striking head.

A further object of the invention is to provide a machine of this character wherein the locking mechanism is contained entirely within the frame.

Further objects of the invention will appear hereinafter.

In the drawing:

Figure 1 is a longitudinal sectional view of my improved stamping machine, the locking mechanism being shown in unlocked, or retracted, position,

Figure 2 is a detail vertical sectional view showing the locking mechanism as it would appear in locking position, and

Figure 3 is an enlarged detail perspective view showing the locking mechanism actuating structure.

The numeral 1 indicates in general the frame of my improved stamping machine. The frame 1 is cast as a single unit. The frame 1 includes a work supporting surface 2 and a raised platform 3. The raised platform 3 is formed, at its inner end portion, with a shallow guide trough 4, which guide trough is formed with a curved rear end wall 5. Pairs of longitudinally spaced headed studs 6 are fixed to the upper surface of the platform 3, near the trough 4, and serve to mount the inking device removably on the frame, as will be set forth in more detail hereinafter.

Associated with the frame 1 is a striking head 7 which is of similar construction to that shown in my co-pending application, Serial No. 294,941. The striking head 7 carries a die plate frame 8 on which is mounted a die plate 9.

The striking head 7 is connected to the frame 1 by pairs of connecting links 10 and 11. The links of the pair of links 10 have their lower ends fixed to a rock shaft 12 which is journaled in the frame 1 beneath the platform 3. A rock shaft 13 is journaled in the frame 1 beneath the surface 2 and swingingly mounts the links of the pairs of links 11 on the frame. The correspond-

ing upper ends of the links are swingingly connected to the corners of the striking head by bolts 14. A handle is connected to one of the links of the pair of links 11 and is manually engaged when it is desired to swing the striking head 7, with the frame 8 and die plate 9 thereon, to operative position in engagement with work on the surface 2.

The striking head 7 is held in a raised inoperative position by mechanism now to be briefly described. This mechanism includes a counter-shaft 16 which has its opposite ends journaled in bushings in the side walls of the frame 1. The counter-shaft 16 is disposed rearwardly of the rock shaft 12 in parallel spaced relation thereto and has levers 18 slidably mounted thereon. The levers 18, as will be seen, are mounted near the opposite ends of the shaft 16 and extend diametrically therethrough. Said levers are threaded at 20 their corresponding outer ends and carry connecting yokes 19 at their corresponding inner ends. Compression springs 20 surround the levers, between the threaded portions thereof and the counter-shaft 16. Wing nuts 21 are screwed 25 on the threaded portions of the levers and provide abutments for the outer ends of the springs 20. The springs are confined between the nuts and the lever and will, therefore, urge said levers rearwardly. Elongated lugs 22 are mounted on 30 the rock shaft 12 and are swingingly connected with the yokes 19 by means of a cross pin 23.

It will now be understood that, when the striking head 7 is swung forwardly, the shaft 12 will be rocked with the result that the lugs 22 will 35 be swung upwardly. This action will, of course, effect forward shifting of the levers 18 transversely of the shaft 16 and compression of the springs 20. When pressure upon the head 7 is released, after a stamping or embossing operation, the springs 20 will return said head to raised 40 inoperative position.

In order to spread ink uniformly on the surface of the die plate 9, I provide an inking roll 24. The ink roll per se is substantially identical 45 in construction to that shown in my co-pending application, Serial No. 324,175, filed March 15, 1940. The mounting structure for the inking roll is somewhat different and, accordingly, will now be described.

Mounted in the frame 1 near the center thereof and near the forward end of the platform 3, and at each side thereof, are guide sleeves 25. The guide sleeves extend throughout the entire height of the frame 1 and are formed with vertically extending opposed slots 26. Slidably

mounted in each of the sleeves 25 is a supporting plunger 27. The supporting plungers 27 are recessed at their upper ends to receive the end trunnions of the inking roll 24. Spring latches may be mounted on the upper ends of the plungers to serve to retain the trunnions in place.

The plungers 27 are normally urged upwardly, to extend above the platform 3 a sufficient distance to engage the inking roll with the surface of the die plate 9 with the head in raised position, by coil springs 30 which are mounted in the sleeves 25 beneath said plungers. Connecting the plungers at their corresponding lower ends and within the frame is a latch rod 31, said latch rod extending through the slots 26 and transversely of said frame and limiting the extent of upward travel of the plungers. The latch rod 31, in addition to the function just mentioned, has another and more important purpose which is that of retaining the inking roll and plungers in locked retracted position when the striking head is in operative position. The mechanism which cooperates with the latch rod for accomplishing this purpose will now be described.

The latch mechanism includes a bracket 32 which is mounted on the under side of the platform 3 of the frame substantially medially thereof. The bracket 32 is relatively wide and provides support for a latch member 33, said latch member being pivotally mounted near the lower end of said bracket by means of a pin 34. The latch member 33 carries a latch plate 35, said latch plate having a partially rolled end edge 36. Normally holding the latch member in raised inoperative position is a spring 37, said spring extending between a point near the upper end of the bracket 32 and a point substantially medially along the latch member.

Mounted near the lower and rear edge of the bracket 32, by means of a pivot pin 38, is a tripping lever 39, said tripping lever having a curved inner end portion 40 and a roller 41, said roller projecting past the rear edge of the bracket and being engageable with a cam 42 which is fixed on the shaft 12 substantially medially of the length thereof. The cam 42 is so positioned that, when the connecting links 10 and 11 are in parallel position, the thinnest portion of the cam will be presented to the roller. However, when the striking head 7 is swung forwardly for rocking the connecting links forwardly and downwardly, the thickest portion of the cam will be presented to the roller 41 with the result that said cam will swing the tripping lever 39 about the pivot pin 38. When this action takes place, the tripping lever will engage the rear edge of the latch member 33 and will swing said latch member about the pivot pin 34 and against the tension of the spring 37. It will be understood that, when the striking head is swung forwardly, the inking roller will be forced downwardly for forcing the plungers and the latch rod downwardly in the sleeves 25. The latch rod will thus be moved to the position shown in Figure 2 and will be engaged by the latch plate 35 of the latch member 33. It will thus be seen that, when the striking head is in forward or operative position, the roller will be maintained in inoperative position by engagement of the latch plate with the latch rod.

As soon as the striking head is raised from the work on the surface 2, the thickest portion of the cam 42 will be shifted upwardly for releasing pressure upon the tripping lever 39. When this

takes place, the spring 37 will raise the latch member to the position shown in Figure 1 and the latch rod will thus be released for permitting raising of the plungers, under the tension of the springs 26, and consequent urging of the inking roll into engagement with the plate 9 on the striking head. As the striking head is rocked back and forth, the inking roll will effectively ink the surface of said plate 9.

Having thus described the invention, what is claimed as new is:

1. In combination with a stamping machine having a frame, and a striking head swingingly connected therewith and being movable to a position engaging a portion of the frame, an inking roll, plungers mounting the inking roll for engagement with stamping means on the striking head, a latch rod connecting the plungers, a latch member cooperating with the rod, and a trip member operable by movement of the striking head to move the latch member in engagement with said rod and retain the plungers and inking roll in retracted inoperative position.

2. In a stamping machine, a frame, a striking head swingingly connected therewith, an inking roll, plungers mounting the inking roll on the frame and normally engaging the inking roll with the striking head, means connecting the plungers to each other, a latch member cooperating with said plunger connecting means, and a trip member operable by movement of the striking head to move the latch member in engagement with the plunger connecting means and retain the plungers and inking roll in retracted inoperative position.

3. In a stamping machine, a frame, a striking head swingingly connected therewith, a die plate on the head, an inking roll movably mounted on the frame, an inking device, a latch rod carried by and movable with the inking roll, a latch member cooperating with said rod, and a trip member operable by movement of the striking head to move the latch member in engagement with the latch rod for locking the inking roll in inoperative retracted position in engagement with the inking device.

4. In a stamping machine, a frame, a striking head, rock shafts carried by the frame, a counter-shaft carried by the frame in close spaced relation to one of said rock shafts, lugs carried by said last-mentioned rock shaft, levers on the counter-shaft, means operatively connecting the levers with the lugs, a cam on the last-mentioned rock shaft, connecting links connecting the rock shafts with the striking head, plungers carried by the frame, an inking roll carried by the plungers, means urging the plungers and inking roll toward the striking head, a bracket on the frame, a latch rod extending between the plungers, a latch member movable on the bracket, and a tripping lever movable on the bracket and engageable with the cam and the latch member, said striking head moving the roller and plungers to inoperative position as it moves to operative position and said cam simultaneously engaging the trip lever for swinging the latch member to engage the latch rod for retaining the plungers and inking roll in locked retracted position.

5. In a stamping machine, a frame, a striking head, means swingingly connecting the head with the frame, an inking roll, means mounting the inking roll for sliding movement on the frame, means urging the inking roll toward the striking head, and means operable by movement

of the first-mentioned means for locking the inking roll in retracted inoperative position, said last-mentioned means including a latch member having a latch plate, a trip lever, a bracket mounting the latch member and trip lever, a latch rod carried by the second-mentioned means, and a cam on the first-mentioned means.

6. In a stamping machine, a frame, a striking head, connecting links swingingly connecting the head with the frame, rock shafts carried by the frame and mounting corresponding lower ends of the connecting links, an inking roll on the frame, means urging the inking roll toward the striking

head, said inking roll being moved to inoperative position upon swinging of the striking head toward operative position, and means automatically operable by movement of the striking head
5 for retaining the inking roll in retracted inoperative position, said means including a cam on one of the rock shafts, a latch member, a tripping lever operatively connecting the latch member with the cam, and a latch rod extending beneath the inking roll and being engageable by the latch member.
